The ornamental design for a nasal-irrigation fitting, as shown and described.

DESCRIPTION

FIG. 1 is a perspective view of a nasal-irrigation fitting showing my new design;

FIG. 2 is perspective view thereof showing an opposing side;

FIG. 3 is a top view thereof;

FIG. 4 is a front view thereof, the rear view, right-side view, and left-side view being mirror images;

FIG. 5 is a bottom view thereof; and,

FIG. 6 is a sectional view through the section 6-6 of FIG. 3. The evenly-spaced broken line depiction of environmental structure represents the medical-fluid delivery device with which the design may be associated and forms no part of the claimed design.
